UNITED STATES PATENT OFFICE.

EBENEZER HILL, OF SOUTH NORWALK, CONNECTICUT.

METHOD OF AND APPARATUS FOR COOLING REFRIGERATING-CARS.

SPECIFICATION forming part of Letters Patent No. 244,602, dated July 19, 1881.

Application filed May 21, 1881. (No model.)

To all whom it may concern:

Be it known that I, EBENEZER HILL, of South Norwalk, county of Fairfield, and State of Connecticut, have invented a certain new and Improved Method of Cooling Refrigerating-Cars and Apparatus for the purpose, of which the following is a specification.

This invention has for its object the cooling of railway-cars for the transportation of such articles as are liable to decay in a temperature a little above the freezing-point—such as meats, fruits, &c.—when in transit between distant points; and the invention consists, first, in a process or method of compressing air drawn from the ordinary atmosphere through which the car or cars may move, conducting said air through suitable conduits to the car or cars to be cooled, and then passing it through an expanding motor-engine to perform work in driving a compressor, the air of which is added to the air from the first compression, and is returned to expanding motor, and thence escapes into the car to be cooled, as will hereinafter appear.

25 The invention further consists in so combining an air-expanding engine for driving an air-compressing engine on a railway-car of suitable construction, and with a prime air-compressor or equivalent source of air-pressure connected to the car, that the exhaust-air from the expanding-engine will cool the car when permitted to escape into it, as will hereinafter appear.

35 The invention further consists in so combining an air-compressing engine on a railway-car and a prime air compressor or reservoir of air under pressure with air-cooling and heat-absorbing conduits and suitable connections that air from the ordinary atmosphere will in its 40 passage through said apparatus serve as a cooling agent for refrigerating purposes, as hereinafter set forth.

45 The invention further consists in so combining an air-compressing locomotive apparatus with a train of cars and suitable connections to air-expanding engines for driving air-compressors on each car to be cooled that a proper supply of compressed air may be furnished to the expanding and compressing apparatus, as will 50 hereinafter appear.

The invention further consists in so combining an air-expanding engine for compression with the ordinary atmospheric or air-brake reservoirs of a train that the proper supply of compressed air may be furnished to operate 55 the air-cooling apparatus, as will hereinafter appear.

The invention also consists in so combining and arranging air-compressing apparatus and reservoirs relatively to a railway-car that by 60 suitable connections a proper supply of air may be furnished to an air-compressing apparatus on a car or cars to be cooled, whereby a proper degree of refrigeration may be produced on the car, as will hereinafter appear.

65 The invention also consists in combining with a car to be cooled by compressed air a thermostat to operate a valve intermediate between the prime motor and the expanding-engine, as will hereinafter appear.

70 In the drawings, Figure 1, Sheet 1, is a plan of the top of a car having the cooling devices located thereon. Fig. 2 is an end view of the same. Fig. 3 is an elevation with the side removed to show cooling-pipes in the interior. 75 A locomotive is also shown in elevation in the same figure. Fig. 4, Sheet 2, is an elevation of a locomotive air-compressor and its engine and boiler as related to the locomotive of the train. Fig. 5 is an elevation of an air-compressor and its reservoirs as they are related to the track and in the act of charging a tank with air to operate cooling-engines on the cars.

80 The same letters refer to like parts in the drawings.

85 At A is represented a car specially constructed for carrying articles required to be kept cool when in transit, and therefore it is made with non-conducting walls and provided with beams and hooks for suspending meats, and with latticed bins for holding fruits, as represented.

90 Upon the top of the car, at B, an air-tight receptacle is constructed with non-conducting walls like an ice-chest to receive an air-expanding engine, as at C, which is operated by compressed air, first, from an independent source, as from a compressing-engine on the locomotive at D, and which may also be used to operate the brakes, or from a special compressor, as at E, Fig. 4, or from a tank or reservoir, as 100

at F, which has been charged at a station; and, second, from air compressed by an engine or pump, at G, which is driven by the expanding-engine itself, and to which it is directly connected as by a piston-rod, shown at H.

It is well-known to engineers familiar with the action of air under pressure that if it performs work when permitted to expand it becomes exceedingly cold; hence the air from the 10 exhaust of the expanding-engine C is permitted to escape directly into the cooling-chest B to cool a brine, or circulating agent to cool the car; or it may escape directly into the car through a nozzle, as at K, and by entering the car with 15 considerable force will cause a circulation in the car, and the warmer air will be thereby displaced and return through suitable openings to the cooling-chest B again; or it may escape into a heat-absorbing and cooling tank, as at 20 L, which is filled with tubes like a surface-condenser, and where it gives its cold to the air from the prime motor on its way to drive the expanding-engine at C. If the supply of air is furnished from the compressor that operates 25 the brakes on the train—as, for example, at M, where the compressor is shown on the side of the locomotive D—then the air will be conducted back through the ordinary pipes and coupling, as at M' and M'', to a reservoir under the car 30 at N, which may supply the air to work the brakes as well as the expanding-engine at C, to which it is conducted through tubes or pipes, as at O and at O', up to the end of the heat-absorbing and cooling tank at L, which is fastened upon the top of the car, and which is filled 35 with small tubes, as shown at P, to absorb the heat of compression and to radiate it and also cool the air from the escaping air from the inside of the car, as already explained. From 40 said tank L, the air under compression is conducted by a pipe at O'' to the expanding-engine, where it performs the work of driving the special compressor at E, which draws its supply from the open air through a long trunk upon the top 45 of the car, as at R, and which is provided with screens of wire-cloth or similar fabric, as at S, to separate the dust; and there may also be a tank filled with sponge or some similar material, as at S', to further serve as a separator to 50 purify the air before it enters the suction side of the special compressor at E.

Instead of supplying air from the outside to the trunk and screens, it may be supplied from the escaping cold air from the car through the 55 outlet-pipe at T, which is provided with a valve to throw the air either into the trunk R or to stop it off, so that the warm air will be compelled to circulate over and over from the car to the cooling-chest and back again through 60 proper openings, as at W, in the said chest, and around the nozzle at K in the top of the car, this last arrangement of the devices shown in a previous application by me for a patent for dynamic refrigeration, in which the expanding-engine is represented in a separate 65 chamber from the chill-room.

The air from the special compressor is forced through a tank like the one shown at L, and which is also fastened on the top of the car, as shown at X, and it is provided with cooling-tubes, as shown at X', and the other end connects with the pipe O', leading from the prime motor or first source of supply for air under pressure, so that the air from the special compressor is used to assist in driving its motor 70 or the expanding-engine. Consequently, after the apparatus has been properly set in operation, the amount of air from the prime motor or source of supply will only be equal to the leakage and deficiency from radiation, &c., 75 and therefore a strong tank may be carried underneath the car or on a special car provided for the purpose, as shown at F, Fig. 5, into which air from a reservoir may be charged 80 at a very high pressure, and then be supplied to the cars by a reducing-valve, as at Z, so that the expanding-engine may be kept in operation when the cars are detached from the locomotive or between stations, if the locomotive is not provided with air-brakes and a compressor, as represented. 85 Another source of supply for air as a prime motor to the compressors on the cars is shown at Fig. 4, where a compressor, as at A', and its engine B' are mounted on a boiler at C', on a 90 car at D', constructed like a tender, to carry coal and water for supplying the boiler, so that such a compressor may supply the required amount of air to any number of refrigerating-cars through proper connections in a train, and 95 thus be independent of the supply from the locomotive, even if it has a compressor to operate the brakes. This arrangement would be preferable where a train of many refrigerating-cars were combined in it, as then any number could 100 be supplied with air from a special prime motor while the locomotive is employed for adding or switching other cars at stations or junction, as 105 is often the case.

The main pipe leading from the source of 110 the air-supply must, of course, be furnished with cocks for each car, and it will be found important to have a thermostat in each car, with a rod extending to a cock, as at a, in the pipe O', so that the supply of air to each car 115 may be controlled according to the temperature desired.

Instead of allowing the air to escape from the expanding-engine directly into the car, it may escape in the cooling-chest, and thence 120 have an outlet to the tank L, where it will give its cold to incoming air and then escape through the funnel at f as warm air, and as explained in a previous application already referred to for dynamic refrigeration. In such a case the 125 cooling-chest will be filled with coils of pipe (shown at c c) that contain a brine or refrigerating liquid supplied from a receptacle at the upper end, and which gradually runs down through the pipes at d d, fastened upon the 130 sides of the car, as shown, and gradually sinks into a cask or receiver at the bottom, whence

it is returned to the upper receptacle by a pumping or lifting device of some kind—as, for example, a pump operated by the oscillating motion of the cars, as patented by one Eliot 5 in 1880. With this kind of an arrangement the liquid in the pipes may be kept sufficiently cold without the use of ice, and thereby a great saving of freight, as well as the cost of the ice, will be effected.

10 The air-compressors at the stations, as shown in the drawings, may also serve a useful purpose in shifting the switches at the junctions or the intersections of roads or tracks by being suitably connected to them by any of the 15 well-known shifting devices where steam or compressed air is used.

A thermometer may also be placed in a proper receiver in connection with the car, as represented at *y*, to indicate the temperature inside.

20 Having thus described my various improvements, I desire to claim—

1. The method of cooling cars for the transportation of meats, fruits, &c., consisting in compressing air drawn from the ordinary atmosphere through which the cars may move, conducting it through suitable conduits to the car to be cooled, and then passing it through an expanding motor-engine to perform work in driving a compressor, the air of which is 25 added to the air from the first compression, and is used by the expanding-engine, and thence escapes into the car to be cooled, as hereinbefore set forth.

2. The combination of an air-expanding engine for driving an air-compressing engine or 35 pump on a railway-car adapted for the transportation of meats, fruits, &c., with a prime air-compressor or other equivalent source of air-pressure connected to the car, so that the 40 exhaust-air from the expanding-engine will cool the car when permitted to enter it, as hereinbefore set forth.

3. The combination of an air-compressing-engine on a railway-car and a prime air-compressor or reservoir of air under pressure with 45 air-cooling and heat-absorbing conduits, and suitable connections in such a manner that air from the ordinary atmosphere will in its passage through said apparatus serve as a cooling agent for refrigerating articles inside of 50 the car, as hereinbefore set forth.

4. The combination of an air-compressing locomotive apparatus with a train of cars and suitable connections to air-expanding engines for driving air-compressors on the cars to be 55 cooled, whereby a proper supply of air may be furnished to the expanding and compressing apparatus, as hereinbefore set forth.

5. The combination of an air-expanding engine for driving a compressor or pump with 60 the ordinary atmospheric or air-brake reservoirs of a train in such a manner that the proper supply of compressed air may be furnished to operate the air-cooling apparatus, as 65 hereinbefore set forth.

6. The combination and arrangement of air-compressing apparatus and reservoirs relatively to a railway-car and the track, that by suitable connections a proper supply of air may be furnished to air compressing and cooling apparatus on the car for refrigerating purposes, as hereinbefore set forth.

7. The combination, with a car to be cooled by compressed air, of a thermostat between the prime motor and the expanding-engine, as 75 hereinbefore set forth.

In witness whereof I have hereunto subscribed my name and affixed my seal in the presence of two subscribing witnesses.
